(57) **CLAIM**

The ornamental design for a putting alignment training device, as shown and described.

DESCRIPTION

FIG. 1 is a top, rear, left-side perspective view showing my new design;

FIG. 2 is top, rear, right-side perspective view thereof;

FIG. 3 is top, front, right-side perspective view thereof;

FIG. 4 is top, front, left-side, perspective view thereof;

FIG. 5 is a top plan view thereof;

FIG. 6 is a left-side view thereof;

FIG. 7 is a right-side view thereof;

FIG. 8 is a rear view thereof; and,

FIG. 9 is a front view thereof.
